US0D1060455S

(12) **United States Design Patent** (10) Patent No.: **US D1,060,455 S**
(45) Date of Patent: ** Feb. 4, 2025

(54) **TRANSFER ROBOT**

(71) Applicant: **W. Gessmann GmbH**, Leingarten (DE)

(72) Inventors: **Martin Eggensperger**, Leingarten (DE); **Andrew Herzig**, Leingarten (DE); **Jonas Bachmann**, Leingarten (DE)

(73) Assignee: **W. Gessmann GmbH**, Leingarten (DE)

(**) Term: **15 Years**

(21) Appl. No.: **29/890,325**

(22) Filed: **Apr. 21, 2023**

FOREIGN PATENT DOCUMENTS

CN 306461759 * 4/2021

Primary Examiner — Patricia A Palasik

(74) Attorney, Agent, or Firm — Orbit IP, LLP; Marc G. Martino

CLAIM

The ornamental design for a transfer robot as shown and described.

DESCRIPTION

FIG. 1 is an isometric view of a transfer robot embodying our new design;

FIG. 2 is a front elevation view of FIG. 1;

FIG. 3 is a rear elevation view of FIG. 1;

FIG. 4 is a right side elevation view of FIG. 1;

FIG. 5 is a left side elevation view of FIG. 1;

FIG. 6 is a top plan view of FIG. 1; and,

FIG. 7 is a bottom plan view of FIG. 1.

1 Claim, 5 Drawing Sheets

See application file for complete search history.
